UNITED STATES PATENT OFFICE.

JOSEPH O. BALDA, OF NEWARK, OHIO, ASSIGNOR TO A. H. HEISEY & CO., OF NEWARK, OHIO.

DESIGN FOR A SURFACE ORNAMENTATION APPLIED TO AN ARTICLE OF MANUFACTURE.

57,806.

Specification for Design.

Patented May 10, 1921.

Application filed August 9, 1917. Serial No. 185,366. Term of patent 14 years.

To all whom it may concern:

Be it known that I, JOSEPH O. BALDA, a citizen of Austria, residing at Newark, Ohio, have invented a new, original, and ornamental Design for a Glass Article, of which the following is a specification.

The drawing shows a surface ornamentation applied to a representative form of goblet, the outline of the goblet being shown

in dotted lines since the specific shape of the goblet or similar article is not essential.

I claim:

The ornamental design for a surface ornamentation applied to an article of manufacture, substantially as shown and described.

JOSEPH O. BALDA.
